UNITED STATES PATENT OFFICE.

CHARLES F. LITTLEJOHN, OF NEW HAVEN, CONNECTICUT, ASSIGNOR OF ONE-HALF TO HARVEY FORD, OF SAME PLACE.

CARRIAGE-BOOT-FLAP HOOK.

SPECIFICATION forming part of Letters Patent No. 234,301, dated November 9, 1880.

Application filed September 13, 1880. (No model.)

To all whom it may concern:

Be it known that I, CHARLES F. LITTLEJOHN, of New Haven, in the county of New Haven and State of Connecticut, have invented 5 a new Carriage-Boot-Flap Hook; and I do hereby declare the following, when taken in connection with the accompanying drawings and the letters of reference marked thereon, to be a full, clear, and exact description of the 10 same, and which said drawings constitute part of this specification, and represent, in—

Figure 1, a front view; Fig. 2, a side view; Fig. 3, the hook detached, perspective.

This invention relates to an improvement in 15 the device used on carriage dash-boards as a means of fastening the boot-flap, the object being a simple and cheap construction, and of such a character that the strain upon the fastener shall tend to make the fastening more 20 secure; and it consists in the construction hereinafter described, and particularly recited in the claim.

A represents the standing strap, and B the free strap, generally arranged with the standing strap above and free strap below.

To the standing strap a metal loop, c, is attached, and to the free strap B a metal hook, D, of peculiar shape, is attached. This hook is made from a strip of sheet metal with a loop, 30 a, at one end, to which the free strap is secured.

The loop a is bent inward and the end d turned downward, so as to form a bearing-surface substantially in line, or slightly forward of the straight line of the strap. The bend e 35 of the loop portion is in rear of the loop a, or point where the free strap B is attached, as seen in Fig. 2.

To engage the free strap with the standing strap, the hook or curved piece D is turned up, as in broken lines, Fig. 2, and the free end d 40 of the hook passed through the loop c until the loop c reaches the bend e. Then the hook is turned down to bring its end d against the free strap B, as seen in Fig. 2. This brings the line of pull or strain at the bend e and in rear 45 of the loop a, or point where the free strap B is attached, so that the strain tends to force and hold the end or suitable bearing-surface d down and against the strap B. To disconnect, reverse the operation.

This construction of hook is simple and cheap, being in two parts only, and of such a nature that they may be readily struck and shaped in dies without the labor of placing the parts together, as required in the usual construction 55 where several parts are employed.

I do not broadly claim a boot-flap hook constructed so that the strain will tend to hold the hook in its closed condition, for such I am aware is not new; but

What I do claim is—

A carriage-boot-flap hook consisting of the curved piece or body D, provided at one end with the inwardly-bent loop a and at the other with a suitable bearing-surface, and adapted 65 to be applied to one of the straps of a carriage-boot, combined with a loop upon the other strap, substantially as described.

CHARLES F. LITTLEJOHN.
